UNITED STATES PATENT OFFICE.

LOUIS G. BRINKMAN, OF DAYTON, OHIO.

GAME APPARATUS.

Application filed July 23, 1926. Serial No. 124,448.

My invention relates to game apparatus and more particularly to a bowling or ten pin alley.

In the drawings the invention has been shown embodied in a miniature or toy bowling apparatus, having at one end of the alley a catapult or impeller for the ball which is mounted for horizontal oscillatory movement, and also transverse sliding adjustment relative to the alley, thus enabling the ball to be impelled through paths of travel upon the alleyway. At the opposite end of the alley, there is provided the usual enclosed pit extending beyond and below

the level of the alley. Associated therewith is a swinging carrier for the pins which is normally located in the bottom of the pit in position to receive the pins as they are knocked from the alley. By the swinging adjustment of such carrier the pins are carried upwardly and forwardly and deposited upon the top of the alleyway in upright and properly spaced or "spotted" positions.

The swinging carrier is suspended from an oscillatory bail or yoke pivoted in the side walls of the pit. This carrier has in its bottom a series of downwardly flanged spaced apertures located and arranged in accordance with the position in which the pins are to be set or "spotted." A sliding closure plate is provided having therein a similarly disposed series of orifices or apertures which are movable into and out of registry with those of the carrier to open and close the apertures by the relative sliding movement of the carrier and closure plate. The sliding closure plate is provided with cam surfaces engaged by the swinging bail or yoke as it approaches the limit of its movement in either direction to shift the plate and bring the apertures into registry over the alley and thereby deposit the pins in their properly spaced positions.

The plate is shifted in the reverse direction, upon the descent of the carrier into the pit, to insure the closure of the apertures preparatory to receiving the pins knocked from the alley, by the engagement of the swinging yoke or bail with the opposite edge of the plate when the pin setter is retracted. In lieu of operating the sliding closure plate by the swinging bail or yoke, it may be oper-

ated to open apertures by contact with the alleyway at the forward limit of the carrier and be retracted by engagement with the rear or end wall of the pit upon retraction of the pin carrier, as is also illustrated in the drawing.

Mounted upon the side of the pit and alley structure is an inclined runway for the return of the balls. This runway is curved upwardly and rearwardly at its forward end, to arrest the momentum of the balls and deposit them upon an elevated receiving track.

The object of invention is to simplify the structure as well as the means and mode of operation of pin setting mechanism for bowling alleys and the like, whereby it will not only be cheapened in construction but will be more efficient in use, positive in operation, uniform in action, easily operated and unlikely to get out of repair.

The further object of invention is to provide a pin setting mechanism of the character described, which will be normally positioned within the pit to receive the pins as knocked from the alley, and which upon operation will deposit the pins upright upon the alley and expeditiously in their proper allocated positions.

The further object of the invention is to provide improved means for automatically operating the sliding closure plate of the pin carrier as the carrier approaches the limit of its range of movement in either direction.

The further object of the invention is to provide improved means for mounting the pin setter for easy and convenient operation and in such a way that none of the operating parts will be disposed in the path of the pins or balls.

A further object of the invention provides a toy or miniature bowling alley which can be constructed economically and be sold for a nominal price, and will further be capable of easy manipulation by children.

A further object of invention provides a bowling structure which may be constructed in its entirety from sheet metal by punch press operation or the like. A further object of invention is to provide an improved catapult or impeller for the discharge of balls and provide an improved form of

mounting whereby such impeller may be variously disposed upon the alley, for varying the direction in which the ball is rolled thereon.

5 With the above primary and other incidental objects in view, as will more fully appear in the specifications, the invention consists of the features of construction, the parts and combinations thereof, and the mode 10 of operation or their equivalents as hereinafter described and set forth in the claims.

In the accompanying drawings wherein is shown the preferred but obviously not necessarily the only forms of embodiment of 15 the invention, Fig. 1 is a perspective view of the miniature bowling alley embodying the several features of invention.

Fig. 2 is a longitudinal sectional view through the rear end of the alley and pit 20 showing the pin setting apparatus in its normal or retracted position.

Fig. 3 is a similar longitudinal sectional view showing the pin setting parts in their operated or advanced position.

25 Fig. 4 is a transverse sectional view of the alley including a front elevation of the pin setting apparatus in the advanced or operated position.

Fig. 5 is a detail sectional view of the 30 ball impeller or catapult.

Figs. 6 and 7 are longitudinal sectional views of the rear portion of the alley and pit illustrating a modified construction of the pin setter and particularly the means 35 for actuating the sliding closure plate, the parts being shown in their normal or retracted position and in the advanced or operated position for depositing the pins upon the alley respectively.

40 Fig. 8 is a detail perspective view.

Like parts are indicated by similar characters of reference throughout the several views.

In a miniature or toy bowling alley shown 45 in the accompanying drawing 1 is the alley-way which is preferably though not necessarily made from sheet metal in tubular form of substantially rectangular cross section. Obviously this alley 1 may be of wood 50 or other material. At the rear of the alley and extending there beyond and below the level of the alley surface is a pit having side walls 2—2 and an end or rear wall 3. The alley 1 extends a limited distance intermediate the side walls 2—2 and is provided 55 at its opposite margins with longitudinal depressions 4—4 simulating the usual gutters. Secured to one side of the structure is an inclined ball return runway 5 having therein 60 adjacent to its rear end an abrupt decline 6 by which the balls are given momentum for their return travel. At its forward end the runway 5 is curved upwardly and rearwardly at 7, throughout substantially a half 65 circle. This upwardly and rearwardly

curved portion of the runway arrests the momentum of the returning balls which are deposited therefrom onto a separate receiving section 8 of the runway, which is overhung by the rearwardly turned terminal 7 70 of the main runway 5.

Located adjacent to the forward end of the alley 1 is a transverse slot or recess 9 in which is mounted for limited horizontal oscillatory adjustment, and for transverse 75 sliding adjustment relative to the alley, a ball impeller or catapult 10. This impeller or catapult comprises a substantially cylindrical or tubular housing, open at its forward end and closed at its rearward end except for a slot through which extends the stem 11 of the spring actuated plunger 12. The plunger 12 is impelled forwardly by a helical spring 13 enclosed within the housing 10. The stem 11 is capable of a limited 80 vertical or oscillatory movement within the guide slot in the closure head at the rear end of the housing 10. This stem is further provided with two spaced shoulders which engage the rear head of the housing 10 at the 85 end of the guide slot to limit the forward movement of the plunger 12 under the influence of the actuating spring 13.

The forward shoulder 14 by its engagement with the head of the housing detains 90 the plunger in its retracted position, with the actuating spring 13 under compression.

Upon a slight depression or downward oscillation of the rearwardly projecting portion of the plunger stem 11, the shoulder 14 100 is disengaged from the head of the housing and the plunger is forcibly projected by the spring 13 until it is arrested by the engagement of the rearmost stop shoulder 15 upon the stem 11 with the end of the housing 10. 105

The bowling ball 16, which in the case of a miniature or toy game apparatus is preferably though not necessarily a large size steel bearing ball, having been placed within the tubular housing 10 of the impeller or catapult, is projected forwardly, by the spring actuated plunger when released, into the group of ten pins 17 placed upon the opposite end of the alley 1. The ten pins are dislodged from the alley and knocked into the 110 pit by the action of the ball 16.

Located within the pit and below the level of the alley to receive the pins knocked therefrom is a pin receiver and setter. Pivoted to the side walls 3—3 of the pit, is a U-shaped bail or yoke 18. Suspended from trunnion studs 19, projecting inwardly from the side arms of the bail or yoke is at midlength position, and therefore eccentric with the pivotal connections with the yoke or bail with the pit walls, is a hanger or swinging carrier comprising an apertured bottom plate 20 and upstanding side walls 21 with which the trunnion studs 19 pivotally engage. The bottom plate 20 is down 115 120 125 130

flanged at the front and rear margins at 22, which flanges engage and rest upon the top of the alley 1, when the pin setter is in its advanced or operated position. The apertures 23 in the plate 20 are spaced from each other and arranged in a triangular grouped relation in accordance with the positions in which the pins are to be deposited or "spotted" upon the alley. The 5 margins of the apertures 23 are downwardly flanged and converge inwardly in directions slightly angular to the vertical, thus serving to guide the deposited pins to their proper location or "spot." The side walls 10 21 of the suspended plate 20 are offset or shouldered to afford fore and aft guides for a reciprocatory apertured receiver for the pins which also serves as the closure for the deposit openings 23 in the bottom plate of 15 the carrier. The reciprocatory receiver 25 is of pan-like construction, being upturned at its forward and rearward margins as at 26 and 27 and having upstanding side walls 28. These upstanding side walls 28 are provided with horizontal slots 29 therein through which project the trunnion studs 19 upon which the carrier and pin setter structure is suspended. These slots 29 permit limited to and fro sliding movement of the 20 pan-like receiver 25 upon its guides 24 and serve to further limit such to and fro movement, as the ends of the slots 29 engage with the studs 19. The bottom of the receiver pan is provided with a series of spaced apertures arranged in triangular grouped relation corresponding with those of the bottom plate 20 and exactly registering therewith when the receiving pan 25 is in its rearward position relative to the plate 20. The apertures in the bottom of the receiving pan 25 are slightly larger than those in the bottom 20 but are similarly formed downwardly projecting flanges which converge inwardly to approximately the size of the apertures in 30 the lower plate 20, thereby forming converging guide chutes when the apertures in respective members are in registry, through which the pins are deposited in the alley 1.

When the receiving pan 25 is at the forward limit of its sliding movement relative to the plate 20, the apertures 23 and 30 of the respective members are out of registry and the openings therefore closed to retain the pins in the receiver. Such is the normal 35 relation of the parts when the carrier and setter apparatus is in its retracted or normal position in the bottom of the pit beyond and below the rear end of the alley 1, as shown in Figs. 1 and 2. In this position the bail or yoke 18 is turned rearwardly with its transverse portion projecting in proximity to the end wall 3 of the pit. 40 As the pins are knocked from the alley into the receiver 25 many of the pins will fall with their butt ends extending into the 45 depressions in the bottom of the receiver pan formed by the closed apertures 30. Any pins otherwise disposed are easily and quickly distributed so that the base or butt end of each pin will extend into or overhang 50 one of the depressions formed by the closed aperture 30 with the pins in variously disposed reclining positions. The operator then grasps the transverse portion of the bail or yoke 18 and swinging the yoke upwardly and forwardly the relatively adjustable parts of the pin setter are carried with it in suspended relation with the trunnion studs 19. The bail or yoke describes an arc of substantially 180 degrees as indicated in 55 Fig. 3 until the dependent flanges 22 of the bottom plate 20 rest upon the surface of the alley 1, as shown by solid lines in Fig. 3. Until this time the receiver pan 25 has remained in its forward position with 60 the apertures 23 and 30 out of registry and therefore closed. The upstanding side wall 28 of the receiver are formed with arcuate margins which afford cam surfaces 31 engaged by the bail or yoke 18 as the latter 65 approaches the limit of its movement and the bottom plate comes to rest on the alley 1. The continued or final depression of the bail or yoke 18 while in engagement with the cam margin 31 of the side walls 28 tend to 70 thereby shift the receiver pan 25 rearwardly within the limits of the slots 29 thereby bringing the apertures 23 of the bottom plate 20 permitting the pin 17 to drop therethrough into upright position upon the 75 alley 1. Sufficient clearness is provided for the trunnion studs 19 in the side walls 21 and 28 of respective members to compensate for this final adjusting movement of the 80 bail or yoke. The connection of the trunnion studs 19 with the carrier parts is slightly below the level of the pivotal connection 31 of the yoke or bail with the side walls of pit, when the carrier or pin setter is in its forward operated position upon the alley. 85 The initial return oscillation of the yoke or bail will lift the carrier or setter parts substantially vertically until they clear the top of the deposited pins 17. The yoke or bail 90 18 is brought upwardly and rearwardly with the carrier or setter suspended therefrom until the latter is again deposited in the pit beyond and below the level of the alley. During such retrograde movement of the 95 carrier, the receiver pan 25 remains in its rearmost position of adjustment relative to the bottom plate 20 with the apertures 30 and 23 in registry. As the carrier parts enter the pit, the rear marginal flange 27 of the receiver pan engages the rear or end wall 100 of the pit and as the carrier parts continue to move rearwardly and downwardly, the receiver pan is thrust forwardly, again moving the apertures out of registry. In 105 case this movement is insufficient, the bail 110 120 125 130

or yoke 18 as it approaches the limit of its rearward or retrograde movement, engages the cam surface 33 formed by the arcuate margins of the side walls 28 of the receiver pan and exerting cam action thereon insures the completion of the shifting movement of the receiver 25. The swinging bail 18 may be relied upon to shift the receiver pan 25 alternately in opposite directions wholly independent of its engagement with the end wall 3 of the pit.

In the event that the receiver is actuated in one direction by its engagement with the wall of the pit, it may be retracted to deposit the pins by arranging the slot 29 as a cam slot such as indicated at 29' Fig. 8. In such construction instead of the bail or yoke engaging the cam face 31 at the limit of its forward movement, the engagement of the trunnion studs 19 within the cam slots 29' would serve to shift the carrier members to bring the apertures 23 and 30 into registry and deposit the pins therethrough.

While in the preferred construction hereinafter described the uppermost carrier member or receiver 25 is shiftable to and fro relative to the bottom plate 20, the arrangement may be reversed and the movable closure member may be provided beneath the receiver or carrier. Such construction is shown in Figs. 6 and 7. In such construction the swinging bail or yoke pivoted to the side walls of the pit carries a suspended receiver 35 having in its bottom the downwardly flanged apertures 30'. Slidingly mounted beneath this swinging carrier 35 is a reciprocatory closure plate 36 having therein a series of corresponding apertures 23'. The plate 36 is provided with a series of tongues or fingers 37 slidingly engaging in slots in the bottom of the carrier 35. At its rear end the sliding closure plate 36 is provided with dependent inclined legs 39, which, as the carrier is lowered to rest upon the top of the alley, engage the end of the alley and by cam action thereon serve to shift the closure plate 36 rearwardly thereby bringing the aperture 23' and 30' into registry to deposit the pins therethrough. Upon return oscillation of the carrier, the rearwardly projecting end of the closure plate 36 engages the end wall 3 of the pit and as the carrier continues rearwardly and downwardly, such sliding plate is returned to its normal position in which the apertures are out of registry, preparatory to receiving the pins knocked from the alley. Projections 40 upward from the bottom of the pit serve as stops or rests to receive the pin carrier in its retracted position. The impeller or catapult housing 10 is provided with downwardly projecting tongues or the T shaped lugs 41 extending through the transverse slot

42 in the alley 1. These tongues retain the impeller or catapult in operative connection with the alley, while permitting its to and fro adjustment transversely of the alley and also permitting an oscillatory adjustment to various angular positions.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect and the invention is, therefore, claimed in any of its forms or modifications within the legitimate and valid scope of the appended claims.

Having thus described my invention, I claim:

1. In a game apparatus of the character described, the combination with a base supporting articles to be knocked therefrom, of a swinging carrier normally positioned below the level of and beyond the margin of the base to receive the article knocked therefrom, swinging links guiding the carrier from such position to a position over the base, the bottom of the carrier being apertured for the deposit of the articles therethrough onto the base, and closure means for the apertures operable upon the to and fro movement of the carrier to open and close the apertures as the carrier approaches the opposite limits of its movement.

2. In a bowling game apparatus, an alley way, a pin receiver normally positioned below the level of and beyond the end of the alley to receive pins knocked therefrom, and movable to and fro from such position to a position over the alley and vice versa, the bottom of the carrier being apertured for the deposit of pins therethrough onto the alley, and closure means for the apertures operable into and out of operative position by the movement of the carrier.

3. In a bowling game apparatus, an alley way, a pin receiver normally positioned below the level of and beyond the end of the alley to receive pins knocked therefrom, and movable to and fro from such position to a position over the alley and vice versa, the bottom of the carrier being apertured for the deposit of pins therethrough onto the alley, closure means for the apertures, a

5. swinging support for the carrier guiding it in its to and fro movement, and means operated by the swinging support as the carrier approaches the limit of its movement 5 for actuating the closure means.
4. In a bowling game apparatus, an alley way, a pin carrier normally positioned below the level of and beyond the end of the alley to receive pins knocked therefrom, and 10 movable thence to a position over the alley, the bottom of the carrier being apertured for the deposit of pins there through onto the alley, means for guiding the carrier in its to and fro movement, and closure means 15 for the apertures by which the apertures are closed when the carrier is in pin receiving position and operable to open the apertures when the carrier is in pin depositing position.
- 20 5. A pin receiver for bowling alleys normally positioned below the level of and beyond the end of the alley to receive pins knocked there from and movable thence to a position over the alley to deposit pins 25 there onto, and vice versa, including two relatively movable apertured plates the apertures of which are shifted into and out of registry by the relative movement of the plates, a cam projection fixedly mounted 30 on one of the plates and movable therewith, and means with which the cam projection engages as the carrier approaches the limit of its movement to shift said apertured plates.
- 35 6. A pin receiver for bowling alleys normally positioned below the level of and beyond the end of the alley to receive pins knocked there from and movable thence to a position over the alley to deposit pins 40 there onto, and vice versa, including two relatively movable apertured plates the apertures of which are shifted into and out of registry by the relative movement of the plates, and means for automatically effecting 45 the relative movement of the apertured plates as the carrier approaches the limit of its movement in either direction.
7. In a toy bowling alley, an alley formed from sheet metal and of elongated rectangular tubular form, a pit located beyond the end of the alley including side and end walls of sheet metal extending to a height above the level of the alley, an adjustable ball impeller located at the end of the alley opposite the pit, and a movable pin receiver normally positioned within said pit.
- 50 8. In a game apparatus of the character described, a bowling alley including a runway, a pit having upstanding walls enclosing one end of the runway, a swinging bail pivotally connected to the opposite walls of the pit, a carrier for pins normally seated within the pit to receive the pins knocked from the alley, said carrier being suspended from the bail and movable from the pit to 55 a position upon the alley in front of the pit by the oscillation of the bail, pin locating openings in the bottom of the carrier, a sliding closure for said openings, and means actuated by said swinging bail as the bail 60 approaches the limit of its movement for actuating the sliding closure.
9. In a game apparatus of the character described, a main structure including a runway, a pin carrier normally positioned beyond and below the level of the runway to receive the pins knocked therefrom, swinging arms upon which the carrier is suspended, by the oscillatory movement of which the carrier is shifted from its normal position 65 beyond and below the level of the runway to a position resting upon the runway and means operated by said swinging carrier arms for depositing the pins from said carrier in predetermined positions upon the runway.
- 75 10. In bowling game apparatus a main structure including a runway, a pin carrier normally positioned beyond and below the level of the runway to receive the pins 70 knocked therefrom, said carrier having a plurality of apertures therein arranged in the order in which the pins are to be set for playing, a closure plate slidably adjustable 80 relative to said carrier, to open and close said apertures therein, a swinging support for said carrier by which the carrier is guided to and fro from its normal position beyond and below the level of the runway to 85 a pin setting position upon the runway and vice versa, and means for actuating the closure plate to deposit the pins upon the runway as the swinging support approaches the limit of its movement.
- 90 11. In an apparatus of the character described, the combination with an alley way and a pit at the end of the alley way, of a receiver and carrier for pins, normally positioned within the pit beyond the end of the alley and below the level thereof, a swinging support for said carrier guiding the carrier through a to and fro arcuate path from its 95 position within the pit to a position over the alley, said carrier having a double bottom, one of the bottom sections being slidably adjustable in relation with the other, the relatively adjustable bottom sections being correspondingly apertured in accordance with the spotting positions of a series of pins upon the alley, the apertures being moved into and out of registry by the relative movement of the sections forming such double bottom, and cam surfaces upon the movable bottom section engaged by the swinging support as the latter approaches the limit of its 100 range of movement in each direction by the camming action of which the bottom section is moved to bring the apertures into registry for the deposit of pins there through when the carrier is in its advanced position.
- 105 12. In a game apparatus of the character described, a carrier for pins normally seated within a pit, a bail pivotally connected to the opposite walls of the pit, a carrier for pins normally seated within the pit to receive the pins knocked from the alley, said carrier being suspended from the bail and movable from the pit to 110 a position upon the alley in front of the pit by the oscillation of the bail, pin locating openings in the bottom of the carrier, a sliding closure for said openings, and means actuated by said swinging bail as the bail 115 approaches the limit of its movement for actuating the sliding closure.
- 120 13. In a game apparatus of the character described, a main structure including a runway, a pin carrier normally positioned beyond and below the level of the runway to receive the pins knocked therefrom, swinging arms upon which the carrier is suspended, by the oscillatory movement of which the carrier is shifted from its normal position beyond and below the level of the runway to a position resting upon the runway and means operated by said swinging carrier arms for depositing the pins from said carrier in predetermined positions upon the runway.
- 125 14. In a game apparatus of the character described, a carrier for pins normally seated within a pit, a bail pivotally connected to the opposite walls of the pit, a carrier for pins normally seated within the pit to receive the pins knocked from the alley, said carrier being suspended from the bail and movable from the pit to 130 a position upon the alley in front of the pit by the oscillation of the bail, pin locating openings in the bottom of the carrier, a sliding closure for said openings, and means actuated by said swinging bail as the bail approaches the limit of its movement for actuating the sliding closure.

upon the alley, and for moving the bottom section to shift the apertures out of registry when the carrier is retracted to its receiving position within the pit.

12. In an apparatus of the character described, the combination with an alley way and a pit at the end of the alley way, of a receiver and carrier for pins normally positioned within the pit, beyond the end of the alley and below the level thereof, a swinging support for said carrier guiding the carrier through a to and fro arcuate path from its position within the pit to a position over the alley, said carrier having a double bottom, one of the bottom sections being slidably adjustable in relation with the other, the relatively adjustable bottom sections being correspondingly apertured in accordance with the spotting positions of a series of pins upon the alley, the apertures being moved into and out of registry by the relative movement of the sections forming such double bottom, a cam surface upon the movable bottom section engaged as the swinging support approaches the limit of its range of movement over the alley by which the movement of the bottom section is effected to bring the apertures into registry to deposit there through pins carried thereby, and means engaged by said movable bottom section as the carrier approaches the limit of its return movement for again shifting the movable bottom section to close the apertures preparatory to again receiving the pins.
13. In the apparatus of the character described, the combination with an alley way and a pit at the end of the alley way, of a receiver and carrier for pins normally positioned within the pit, beyond the end of the alley and below the level thereof, a swinging support for said carrier guiding the carrier through a to and fro arcuate path from its position within the pit to a position over the alley, said carrier having a double bottom, one of the bottom sections being slidably adjustable in relation with the other, the relatively adjustable bottom sections being correspondingly apertured in accordance with the spotting positions of a series of pins upon the alley, the apertures being moved into and out of registry by the relative movement of the sections forming such double bottom means for shifting the movable bottom section to bring the apertures into registry for the deposit of the pins there through when the carrier is positioned over the alley, and means for moving the apertures out of registry when the carrier is retracted.

14. In a construction of the character described, swinging arms, a carrier member suspended from the swinging arms in eccentric relation with their center of oscillation, said carrier having a series of spaced aper-

tures in the bottom thereof, a sliding closure member for the apertured bottom of the carrier which by its to and fro adjustment opens and closes the apertures a stationary stop member engaged by said sliding closure to effect its movement relative to the carrier as the swinging arms approach the limit of their movement in one direction and means for relatively shifting the closure and carrier in the opposite direction as the swinging arms approach the opposite limit of their range of movement.

15. In a construction of the character described, swinging arms, a carrier member suspended from the swinging arms in eccentric relation with their center of oscillation, said carrier having a series of spaced apertures in the bottom thereof, a sliding closure member for the apertured bottom of the carrier which by its to and fro adjustment opens and closes the apertures, a cam portion stationarily mounted upon the movable closure means engaging with said cam portion as the swinging arms approach the limit of their range of movement for shifting said closure member relative to said apertures.

16. In a construction of the character described, swinging arms, a carrier member suspended from the swinging arms in eccentric relation with their center of oscillation, said carrier having a series of spaced apertures in the bottom thereof, a sliding closure member for the apertured bottom of the carrier which by its to and fro adjustment opens and closes the apertures, a cam stationarily mounted upon the movable closure and means carried by the swinging arms engaging such cam portion as the arms approach the limit of their range of movement for shifting the closure relative to said apertures.

17. In a construction of the character described, swinging arms, a carrier member suspended from the swinging arms in eccentric relation with their center of oscillation, said carrier having a series of spaced apertures in the bottom thereof, a sliding closure member for the apertured bottom of the carrier which by its to and fro adjustment opens and closes the apertures, a cam portion stationarily carried by the closure, and means engaging therewith as the swinging arms approach the limit of their range of movement for shifting the closure relative to the apertures.

18. In a construction of the character described, swinging arms, a carrier member suspended from the swinging arms in eccentric relation with their center of oscillation, said carrier having a series of spaced apertures in the bottom thereof, a sliding closure member for the apertured bottom of the carrier which by its to and fro adjustment opens and closes the apertures, an ex-

- 5 tension on said closure member and means with which the extension contacts as the swinging arms approach the limit of their range of movement for shifting the closure relative to the apertures.
- 10 19. In a construction of the character described, a substantially U shaped bail, a supporting structure to which the ends of the U shaped bail are pivoted, for to and fro oscillatory motion, a carrier having an apertured bottom, trunnion studs at mid length positions of the arms of the U shaped bail upon which the carrier is suspended, a slidably adjustable false bottom for said carrier having apertures therein movable into and out of registry with those of the carrier bottom by a to and fro sliding adjustment of said false bottom, and cam shaped side portions upon the sliding false bottom engaged by the transverse portion of the bail as the bail approaches the limit of its range of movement in each direction by which the false bottom is moved in alternate directions.
- 15 20. An alley way for a toy bowling alley, comprising a single section of sheet metal formed into an elongated tubular body of substantially rectangular cross section having integral top, bottom and side walls.
21. As an article of manufacture, an alley way for toy bowling alleys including an elongated hollow body of sheet metal having substantially parallel top and bottom and side walls spaced one from the other and a return way for balls secured to the side of said body, said return way comprising an elevated rearward section and a lower forward section connected by an intermediate inclined portion, the forward end of the lower section being curved upwardly and rearwardly and a receiving section for balls overhung by the upwardly and rearwardly curved portion of the return way.
22. As an article of manufacture, an alley way for toy bowling alleys, including an elongated hollow body of sheet metal having substantially rectangular cross sectional contour, and vertical wall extensions of sheet metal extending beyond one end of the hollow body and above the level thereof and joined transversely one to the other to form a pit at the end of the hollow body portion for the reception of pins knocked therefrom and a return way for balls attached to the side of said structure.

In testimony whereof, I have hereunto set my hand this 9th day of July A. D. 1926.

LOUIS G. BRINKMAN.
